UNITED STATES PATENT OFFICE

152,455

DESIGN FOR A BOTTLE

Julius Braun, Chicago, Ill., assignor to W. Braun Co., Chicago, Ill., a copartnership consisting of Julius Braun, Morris Braun, and Eve C. Erenberg

Application July 19, 1947, Serial No. 140,398

Term of patent 14 years

(Cl. D58—8)

To all whom it may concern:

Be it known that I, Julius Braun, a citizen of the United States, residing at Chicago, Illinois, has invented a new, original, and ornamental Design for Bottle, of which the following is a specification, reference being had to the accompanying drawing, forming a part thereof.

I claim:

The ornamental design for a bottle, substantially as shown.

JULIUS BRAUN.
